DOUBLE SIDE IRONER

Forrest J. Couch, Cincinnati, Ohio, assignor to
 The American Laundry Machinery Company,
 Cincinnati, Ohio, a corporation of Ohio

Application April 7, 1930, Serial No. 442,125

8 Claims. (Cl. 68—9)

My invention relates to ironing machines. It relates, particularly, to ironing machines adapted to be used in laundries for ironing flat work such as sheets, towels, or the like, and comprises a plurality of rolls cooperating with a plurality of steam chests together with suitable mechanism for feeding the material to be ironed between the rolls and chests in a continuous line.

Heretofore, many flat work ironing machines have only been adapted to iron one side of the goods during one passage through the machine, the goods being passed through the machines twice to iron both sides thereof. The machines as previously constructed covered a large amount of floor space; the heated steam chests were exposed and radiated great quantities of heat into the room causing discomfort to the operators; the pressure between the rolls and the steam chests could not be adjusted accurately and the pressure exerted between the rolls and their respective cooperating steam chests had to be ascertained individually and varied or adjusted individually; only natural circulation of air was provided to dry the goods; the rolls were so mounted that the entire weight of each roll had to be lifted to make adjustments; and the work done by such a machine was slow and inefficient.

The primary objects of my invention are to iron both sides of the goods during a single passage thereof through the machine; to reduce radiation of heat from the machine; to provide improved means whereby the pressure between all of the rolls and their respective cooperating steam chests can be varied in unison independent of the operation of the machine; to provide improved means for indicating the position of the chests relative to the rolls and thereby the pressure exerted on the rolls by the chests; to so construct the chest supporting means that each chest is free to individually adjust itself to its cooperating roll; to provide a forced circulation of air and a longitudinal conveyor for the goods within the machine to increase the drying properties of the machine; to so construct the machine that similar parts are interchangeable; to so mount the steam chests that the weight of one will tend to counter-balance the weight of the other; to provide an adjustment whereby each chest may be set in exact parallel relation with its cooperating roll; to provide means for disconnecting each roll individually from the driving mechanism therefor; to provide a simple and efficient drive for the rolls; and to arrange the mechanism in a compact form within a closed

housing so as to occupy minimum floor space and be convenient to operate in such manner as to do efficient work in the shortest possible time and resulting in a strong, durable and relatively inexpensive mechanism.

In accomplishing the above objects, my invention contemplates the provision of a machine wherein three padded rolls are provided which cooperate with five steam chests together with suitable mechanism for driving such rolls. However, the number of rolls and chests may be varied without departing from the scope of my invention. The apparatus is such that the preferred cycle of operation comprises first ironing the front face of a piece of flat work, then the back face and finally the front face during a single passage of the work through the machine. With the device disclosed by my invention, the front face is first ironed by being pressed against the smooth surface of a hot steam chest, the back face is then ironed by being pressed against the smooth surfaces of two hot steam chests successively and then the front face is again ironed by being pressed against the smooth surfaces of two hot steam chests successively. Suitable co-operating mechanism for the rolls and chests is also provided as will be hereinafter apparent.

Various other objects and advantageous features of my invention may be seen in the following detailed description and one embodiment thereof may be seen in the accompanying drawings wherein similar characters of reference designate corresponding parts, and wherein:

Fig. 1 is a central vertical cross section through a machine constructed in accordance with my invention; Fig. 2 is an elevation of one end of the same machine with the end of the housing removed; Fig. 3 is a plan view partly broken away; Fig. 4 is an end view with parts omitted showing the manner of mounting the steam chest; Fig. 5 is an end view showing the air suction pipe connections; Fig. 6 is an end view showing the steam pipe connections; Fig. 7 is an elevation showing the clutch connection for the ironing roll drives; Fig. 8 is a sectional view taken on the line 8—8 of Fig. 7; Fig. 9 is an elevation showing the means for adjusting the steam chests laterally with respect to the longitudinal axis of the rolls; and Fig. 10 is a sectional view taken on the line 10—10 of Fig. 9.

Referring to the drawings, the frame of a machine constructed in accordance with my invention consists of a right-hand side frame 11, a left hand side frame 12, and longitudinal end frames 13 and 14 rigidly connecting the side frames to

gether. As shown, three padded rolls 15, 16 and 17 preferably of the same diameter, are rotatably mounted and extend parallel to each other between the end frames 11 and 12, the roll 15 being located directly above the roll 17 and the roll 16 being located a short distance to the rear of and equi-distant from the rolls 15 and 17. Such rolls are rigidly mounted on shafts 18 projecting beyond the ends thereof and mounted in suitable bearings (not shown) on the frames 11 and 12. Adjacent the frame 12, the shafts 18 are operatively connected at one of their ends to sprocket wheels 19, as shown in Fig. 2 by means of a clutch mechanism illustrated in Figs. 7 and 8 and comprising a spring pressed pin 20 mounted to slide in a suitable socket 21 provided in each sprocket wheel 19 and so arranged that its end will register with and slide into any one of four holes or openings 22 in a radial flange or hub 23 keyed to each shaft 18. Thus, when the spring pressed pin 20 is within one of the holes or openings 22, the shaft 18 is operatively engaged with the sprocket wheel adjacent thereto and will be rotated in unison therewith.

When it is desired to disconnect the shaft 18 and the roll carried thereby from the sprocket wheel adjacent that particular shaft, it is only necessary to withdraw the spring pressed pin 20 from its cooperating hole or opening 22 against the resistance of the spring 24 and to retain the pin 20 in its retracted position, each pin is provided with an integral elongated extension 25 which, when the pin is partly rotated about its longitudinal axis, will come to rest in a notch 26 provided in a raised portion 27 integral with the sprocket wheel 19. To again clutch the shaft 18 to the sprocket wheel 19, the pin 20 may be further drawn longitudinally into the socket and turned so that the extension 25 will clear the groove 26 whereupon the pin will be pushed longitudinally in the opposite direction by the spring 24 and will engage the first hole or opening 22 in the radial flange or hub 23 on the shaft 18 with which it co-acts, thereby locking the shaft and sprocket together.

Secured to the frame members of the machine in such position as to cover the working parts thereof is a suitable housing 28 and back of the housing a motor 29 is mounted, preferably on the floor, which has a sprocket 30 rigidly mounted on the drive shaft 31 thereof. A system of reduction gearing is mounted within the housing 28 and consists of a large sprocket 32 mounted to rotate with a small gear 33 that meshes with a large gear 34 adapted to rotate with a small sprocket 35, the small sprocket 35 being connected by an endless chain 36 to the sprocket wheels 19 and the motor sprocket 30 being connected by a sprocket chain 37 with the large sprocket wheel 32 whereby the rolls 15, 16 and 17 may be rotated in unison in the proper direction and at a reduced speed with relation to the speed of the motor 29.

The direction of travel and the path of the sprocket chain 36 is from the small sprocket 35 about the adjustable idler or tightener 38, idler 39, about the first sprocket wheel 19 clockwise, the second sprocket wheel 19 counter-clockwise, about the remaining sprocket wheel 19 clockwise, and thence about the idler sprocket 40 to the sprocket 35. Such sprocket 40 is rigidly mounted on a shaft 41 which extends substantially from one side of the machine to the other and is mounted in suitable bearings (not shown) provided in the side frames 11 and 12.

Referring to Figs. 1 and 4 of the drawings,

large steam chests 42, 43 and 44 are disposed beneath the rolls 15, 16 and 17, respectively, the sides of the chests toward the rolls being made concave to conform with the contour of the outer surface of the padding on the rolls and the ends of the chests extending a short distance beyond the ends of the rolls where they are flexibly connected to suitable rock arms 45, 46 and 47 by means of which each steam chest is moved towards and away from its cooperating roll as desired and by means of which the chests are moved out of contact with the rolls when the machine is not in operation. The respective rock arms are provided at each end of the machine. As shown in Fig. 4, the rock arms 45 and 46 carry 15 and are adapted to press two small steam chests 48 and 49 against the upper side of the rolls 16 and 17 respectively or to move such chests away from the respective rolls.

The three large chests 42, 43 and 44 are similarly connected at each of their ends to the respective pairs of rock arms 45, 46 and 47, and, therefore, only one such connection need be described. Each connection consists of bolts 50 extending through lugs 51 on the steam chest 25 and thence upwardly through the cooperating rock arm, the threaded ends of such bolts being provided with nuts 52 that bear against resilient members or compression springs 53 disposed between the under surface of each nut and the upper surface of the rock arm and surrounding the bolts 50. These springs are of the expanding type and provide a means for effecting a stiff yielding upward pull on the steam chest.

About midway between the two bolts 50 that are provided at each end of each chest, each rock arm is provided with an arcuate guide surface 54 struck from the center about which the rock arm is pivoted and arranged to slide on a friction block 55 which is pivotally mounted on eccentric pin 56 anchored in a boss on the chest as shown in Figs. 9 and 10. The chest is free to rock about the pin 56 as a pivot to adjust itself to the surface of its cooperating roll while still being tightly pressed against the roll when the rock arm is moved about its pivot in the proper direction and will be directed toward and from the roll in a substantially straight line at all times. Further, the longitudinal axis of the chest can be shifted laterally with respect to the longitudinal axis of the roll with which it co-operates by turning the eccentric pin 56 in its socket. A set screw 57 is provided to anchor the eccentric pin 56 in its adjusted position in the chest.

The two small steam chests 48 and 49 being disposed above the respective rock arms 45 and 46, their weight exerts more than the desired amount of pressure against the respective rolls. Therefore, springs 58 are interposed between the upper surfaces of the rock arms and the lower surfaces of lugs 59 that extend outwardly from the ends of the chests, the lugs being provided with suitable sockets that serve as guides for the uppermost ends of the springs 58. Follower blocks 60 are disposed within the sockets in the lugs 59 so as to bear against the upper ends of the springs 58 and be movable within the sockets. Set screws 61 are provided in order that the follower blocks may be moved upwardly or downwardly to vary the compression of the springs 58 and thereby vary the pressure exerted on the respective rolls by the small steam chests 48 and 49. Similar to the construction described in connection with the supporting means for the steam

5 chests 42, 43 and 44, the rock arm is provided with an arcuate guiding surface 54 struck from the center about which the rock arm is pivoted, and a friction block which is arranged to slide 10 on the guide surface and which is pivotally mounted on an eccentric pin as hereinbefore described and as shown in Figs. 9 and 10, so that the chests 48 and 49 will be free to rock about the eccentric pin as a pivot to adjust themselves 15 to the surfaces of the rolls while pressing tightly against the rolls when the rock arms are moved about their pivots and the longitudinal axes of the chests may be adjusted laterally.

10 The pair of rock arms 45 which are adapted to move the chests 42 and 48 into and out of proper relation with the rolls 15 and 16 are pivotally mounted between the rolls 15 and 16 on stub shafts 62 whereby movement of the rock arms in either direction about their pivots 62 15 will move the chests 42 and 48 either into or out of engagement with the rolls 15 and 16 simultaneously. As shown in Fig. 4, the ends of the arms 45 that support the large steam chest 42 have a downwardly extending portion 63 at their 20 forwardmost ends which carries roller elements 64 adapted to ride upon a cam 65 mounted on a shaft 66 that is journaled in the side frames 11 and 12.

25 Adjacent the frame 11, the shaft 66 is provided with a worm gear 67 adapted to mesh with a worm 30 68 driven by a gear 69 meshing with a gear 70 mounted on a shaft 71 and adapted to be driven by a sprocket and chain connection with a motor 72. This structure is clearly shown in Fig. 5. 35 The motor 72 is preferably of the reversible type with the proper control mechanism therefor, whereby the shaft 66 carrying the cam 65 may be caused to rotate in either direction and the cam 65 likewise rotated. Movement of the cam 65 is 40 effected independently of the operation of the remainder of the machine due to the fact that a separate mechanism and power unit are used.

45 With this construction, when the large part of the cam 65 engages the rollers 64 on the forwardmost end of the rock arms 45, the forwardmost ends of the rock arms carrying the chest 42 will be moved upwardly and the opposing ends of the rock arms carrying the small chest 48 will be moved downwardly whereby the respective steam 50 chests will be moved into effective relation with the rolls 15 and 16. Likewise, when the cam 65 is rotated so that the rollers 64 engage the small part thereof, the respective ends of the rock arms 45 will be moved reversely to that just described 55 and the respective steam chests 42 and 48 will be moved out of cooperative relation with the rolls 15 and 16.

60 The intermediate set of rock arms 46 are likewise pivotally mounted between the rolls 16 and 17 on the stub shafts 73 and the ends of the rock arms on which the small chest 49 is mounted have upwardly extending portions carrying rollers 74 that are adapted to ride upon a cam 75 likewise rigidly mounted on the shaft 66 and 65 driven by the same motor 72 and cooperating mechanism hereinbefore described. However, the cam 75 is oppositely disposed relative to the cam 65 whereby the larger portion of the cam 75 extends downwardly and the larger portion of the cam 65 extends upwardly. Thus, when the 70 large part of the cam 75 is in its extreme downwardmost position the small chest 49 has been moved downwardly into cooperative relation with the roll 17 and the large chest has been moved upwardly into cooperative relation with the roll 16 75

and when the small portion of the cam contacts with the roller 74 the respective chests have been moved out of cooperative relation with the rolls. As will be seen in Fig. 4, the lower rock arms 47 are pivotally mounted at one end thereof on the stub shafts 76 immediately below the stub shafts 73, the stub shafts 62 and 73 and 76 being disposed in the same vertical line whereby the relative positions of the arms 47 to the roll 17 may be identical with the relative positions of the forwardmost ends of the arms 45 supporting the large chest 42. The forwardmost ends of the arms 47 have downwardly inclined portions 77 which are connected by means of links 78 with the downwardly extending portions 63 of the arms 45. 15 Thus, upward movement of the forwardmost ends of the arms 45 to move the chest 42 into cooperative relation with the roll 15 causes simultaneous upward movement of the arms 47 to move the chest 44 into cooperative relation with the 20 roll 17 and, since the arms are each moved simultaneously by the cams 65 and 75 that are rigidly mounted on the same shaft, it will be apparent that all of the steam chests will be moved toward and away from their cooperating rolls in 25 unison. The weight of the two chests 42 and 44 being greater than the weight of the chest 48, the rollers 64 will always be held in contact with the cam 65 and, likewise, the weight of the chest 43 being greater than the weight of the chest 49 the 30 rollers 74 will always be held in contact with the cam 75.

35 When the machine is assembled and the springs supporting the respective chests are so regulated or adjusted that each chest is pressing against its 40 cooperating roll at a predetermined pressure, slightly greater, preferably, than the highest pressure ever required when the larger part of the cams 65 and 75 are contacting with the rollers 64 and 74, the position of the cam shaft 66 and 45 50 the resultant position of the cams 65 and 75 determines what pressure is exerted between the respective chests and the respective rolls. To enable the operator to observe and to adjust the position of the cam shaft 66 and cams carried thereby, an indicator 79 and a dial 79' graduated to indicate the pressure exerted by the chests on the rolls in certain positions of the cam shaft and cams are provided as shown in Fig. 2, the indicator hand being adapted to be moved in unison with the cam shaft 66 by means of a suitable chain and sprocket connection 80. One end of the shaft 71, see Fig. 5, extends beyond the housing at the front side of the machine and is provided with a square portion so that it may be turned manually to rotate the cam shaft 66 and 55 the cams carried thereby to the proper position to secure the desired pressure between all of the respective chests and their cooperating rolls. 60

65 With my invention the conventional system of tapes and ribbons is employed to carry and guide the material through the machine. As shown, the endless tapes 81 pass around the roll 15, thence over the rear end of the chest 42, thence under chest 48, thence around the spring pressed spools or tighteners 82 and back to and around the roll 15. Also, the endless tapes 83 pass around the roll 16 thence over the forward end of the chest 43, thence under the chest 49, thence around the 70 spring pressed spools or tighteners 84 and back around the roll 16. The tapes 85 pass around the roll 17, thence over the rear end of the chest 44, thence under the rod 86, thence on an incline out of the machine housing and upwardly around the spring pressed spools or tighteners 87, thence 75

down an incline and under a rod 88 and thence back around the roll 17.

An inclined feed table 89 is supported by brackets 90 secured to the end frames of the machine 5 and at the forwardmost end thereof which is in front of the roll 15. A rod 91 extends transversely of the machine and entirely across the face of the roll 15 and its ends are secured in the frames 11 and 12. A driving roller 92 that is rotatably mounted at the lower forwardmost end of the feed table extends the full width of the feed table and suitable endless feed ribbons 93 pass upwardly from the feed table, around the transverse rod 91 downwardly under the feed table and thence 10 around the driving roller 92 and upwardly over the feed table again.

The driving roller 92 is mounted on a shaft supported in adjustable bearings secured in the brackets 90 and one end of such shaft is provided with a sprocket 94 as shown in Fig. 2 connected by a sprocket chain 95 to one sprocket 96 secured on a shaft 97 mounted in bearings on the end frame 12. Each sprocket 96 and shaft 97, is, in turn, driven by a sprocket chain 98 passing around a sprocket 99 on the shaft 18 which supports the roll 16 and is adapted to be rotated therewith. With this construction, said ribbons 93 will travel along the feed board 89 in substantially the same rate of speed at which the periphery of the roll 16 25 travels and, since the rolls travel at the same rate of speed due to the driving connection therebetween, the feed ribbons 93 travel at substantially the same rate of speed as the periphery of all of the feed rolls.

To insure the proper passing of the material fed to the machine in a flat condition between the chest 42 and the roll 15, a set of endless tapes or feed belts 100 are provided above the upper part 30 of the feed table 89, these tapes passing upwardly along the table, thence upwardly above the spring pressed spools or tighteners 101, thence forwardly above the feed table and about a trip roller 102 and thence back to the starting point and upwardly again along the feed table 89.

The trip roller 102 is mounted to rotate in the free ends of links 103 having their other ends pivoted in the free ends of arms 104 rigidly fixed on a rock shaft 105 which is loosely pivoted in the end frames 11 and 12. A short crank arm 106 is rigidly mounted on the rock shaft 105 the crank arm having its free end connected by a link 107 to the operating arm of an electric switch structure 108 connected in the circuit that supplies power for operating the motor 29 to actuate the machine. With this construction, when the trip roller 102 is moved about the shaft 105 as a pivot either manually or by articles to be ironed pressing against it, the power supply to the motor 29 will be shut off and the machine will stop operating 45 due to the fact that a contact in the switch structure 108 will be broken. However, when the obstruction is removed from under the trip roller 102 or when no manual force is exerted thereon such roller will fall by gravity towards the feed 50 table 89 to again cause contact to be made in the switch 108 and thereby cause operation of the motor 29.

Brackets 109 extend outwardly from the opposite or delivery side of the machine and carry an 55 inclined delivery ribbon bracket 110 at the extreme rear edge of which is mounted a rod 111 that is secured in brackets provided therefor. Endless delivery ribbons 112 pass upwardly along the inclined delivery ribbon bracket 110, thence 60 around the rod 111, thence downwardly along

the inclined bracket into the housing of the machine and thence upwardly around a driving roll 113 and again upwardly along the surface of the bracket 110. Such driving roll 113 is rigidly mounted on the shaft 41 which is driven by the chain 36 at such speed as to cause the delivery ribbons 112 to travel at approximately the same speed as the periphery of the ironing rolls 15, 16 and 17 and it will be noted that the major portion of the delivery ribbons 112 is disposed within the 10 housing where the air is at a relatively high temperature due to the heat of the ironing members whereby the goods will be completely dried before leaving the delivery ribbons 112.

Some of the material or goods about to be delivered tends to cling to the delivery ribbons 112 and pass with the same back into the machine. To prevent such non-delivery of the goods, a series of guides or stripper bars 114 are provided between the respective delivery ribbons 112 adjacent the rod 111, these guides or stripper bars being secured to the upper edge of the delivery table 110 and so arranged as to separate the goods from the ribbons as the ribbons pass downwardly around the rod 111 whereby the goods may fall by 25 gravity upon a suitable table or into a suitable receptacle. The delivery table 110 is preferably made adjustable towards and away from the driving roll 113 so as to enable tightening or loosening of the delivery ribbons 112 as desired.

To insure that the goods fed to the machine follows the proper course through the machine, suitable guides 115 preferably of sheet metal are provided at the upper rear edge of chest 43 and the upper front edge of chest 44 and are held in 30 proper position by brackets secured to the chests 43 and 44. Also, the rolls 15, 16 and 17 are of hollow construction to carry away the moisture passing from the goods being ironed through the padding and through perforations in the surface of the rolls to the interior thereof and one end of each roll has its shaft provided with a central bore or hole forming communication between the interior of the roll and a suction pipe 116, see Fig. 5, connected to the ends of the shafts 45 by means of swivel joints and leading to the suction end of a fan 117 which is driven by a motor 118. Such moisture may be, in turn, delivered to the exterior of the machine or some other suitable point by the fan 117. A hood 119 within the 50 housing 28 is connected to the suction pipe 116 by suitable conduits whereby the heat and moisture communicating with hood 119 may be drawn out of the housing and delivered to the atmosphere or some other desired point by the fan 117.

In an ironing machine of this type it is necessary to provide a means for injecting steam into the chests of the machine. In this apparatus a main steam supply pipe 120, see Fig. 6, leads from a suitable source of supply and branches 60 121 lead from the main supply pipe to the steam chests 42, 43, 44, 48, and 49. Such branches 121 are so arranged that the moisture from the condensation taking place within the steam chests will drain to the main supply pipe 120 and a portion of each branch is made flexible to permit free movement of the chests with relation to the rolls.

In the operation of this device, assuming that the material to be ironed is fed to the machine 70 with the normal upper side thereof upwardly, the material is first spread upon the moving feeding ribbons or tapes 93 by which it is carried between the feed ribbons 93 and tapes 100, thence downwardly between the roll 15 and the steam chest 42 75

whereby it is ironed on the lower side thereof since the lower side of the material contacts with the steam chest 42; thence the material passes successively between the roll 16 and the small chest 43 and between the roll 16 and the large chest 43 whereby the upper side is ironed since that side contacts with the chests 43 and 44; thence the material passes successively between the small chest 43 and the roll 17 and between the large chest 44 and the roll 17 whereby the lower side thereof is ironed again since that side is in contact with the steam chests 43 and 44; thence the material is carried onto the delivery ribbons 112 whereon it is thoroughly dried by the heat within the housing 23 and is then delivered outside of the machine and onto the delivery table 110.

From the preceding description, it will be seen that I have provided a device wherein material fed to the machine is first ironed on the lower side thereof by one chest and roll, ironed on the upper side by two chests cooperating with a single roll, and finally ironed again on the lower side by two chests cooperating with a single roll. Such system of ironing has been found to be advantageous in that both sides of the goods are ironed in one passage through the machine whereby handling of the goods more than once is eliminated. Another advantageous feature resides in the fact that the pressure of each steam chest against its cooperating roll can be individually adjusted and, when once properly adjusted the pressure of all chests against their cooperating rolls can be varied as desired accurately and simultaneously.

Still another advantageous feature resides in the fact that the temperature of all the chests can be accurately controlled as well as the temperature within and around the machine. A further advantageous feature resides in the fact that the machine is relatively simple and compact requiring but a minimum floor space while making possible maximum production.

What I claim is:

1. An ironing machine comprising, a frame, a pair of vertically spaced rotatable padded rolls, a rotatable padded roll spaced laterally and substantially equidistantly from said first named rolls and having a diameter greater than the spaces between said rolls, an ironing chest having an ironing face extending from one side and substantially the level of the horizontal axis of the upper roll, underneath the same and to a point adjacent the top side of the roll spaced laterally therefrom, an ironing chest having an ironing face engaging the top side of the laterally spaced roll, and a single supporting means for said two ironing members including a member pivotally mounted intermediate said ironing members with the ironing members so disposed thereon relative to the pivot thereof that the weight of one chest tends to counter-balance the weight of the other.

2. An ironing machine comprising, a frame, a pair of vertically spaced rotatable padded rolls, a rotatable padded roll spaced laterally and substantially equidistantly from said first named rolls and having a diameter greater than the spaces between said rolls, an ironing chest having an ironing face extending from one side and substantially the level of the horizontal axis of the upper roll, underneath the same and to a point adjacent the top side of the roll spaced laterally therefrom, an ironing chest having an ironing face engaging the top side of the laterally spaced roll, a single supporting means for said

two ironing members including a member pivotally mounted intermediate said ironing members with the ironing members so disposed thereon relative to the pivot thereof that the weight of one chest tends to counter-balance the weight of the other, and means for moving said supporting member about its pivot to bring the ironing members carried thereby into engagement with their respective rolls in unison.

3. An ironing machine comprising, a frame, a pair of vertically spaced rotatable padded rolls, a rotatable padded roll spaced laterally and substantially equidistantly from said first named rolls and having a diameter greater than the spaces between said rolls, an ironing chest having an ironing face extending from one side and substantially the level of the horizontal axis of the upper roll, underneath the same and to a point adjacent the top side of the roll spaced laterally therefrom, an ironing chest having an ironing face engaging the top side of the laterally spaced roll, and a single supporting means for said two ironing members including a supporting member pivotally mounted intermediate said ironing members with the ironing members so disposed thereon relative to the pivot thereof that the weight of one chest tends to counter-balance the weight of the other, an ironing chest having an ironing face extending from one side and substantially the level of the horizontal axis of the laterally spaced roll, underneath the same and to a point adjacent the top side of the lower vertically spaced roll, an ironing chest having an ironing face engaging the top side of the lower vertically spaced roll, all of said ironing members being arranged to provide for continuous passage of work from the upper vertically spaced roll, around the laterally spaced roll, and to and around the lower vertically spaced roll, and a single supporting means for said last two ironing members including a supporting member pivotally mounted intermediate such ironing members with the ironing members so disposed relative to the pivot thereof that the weight of one chest tends to counter-balance the weight of the other.

4. An ironing machine comprising, a frame, a pair of vertically spaced rotatable padded rolls, a rotatable padded roll spaced laterally and substantially equidistantly from said first named rolls and having a diameter greater than the spaces between said rolls, an ironing chest having an ironing face extending from one side and substantially the level of the horizontal axis of the upper roll, underneath the same and to a point adjacent the top side of the roll spaced laterally therefrom, an ironing chest having an ironing face engaging the top side of the laterally spaced roll, a single supporting means for said two ironing members including a supporting member pivotally mounted intermediate said ironing members with the ironing members so disposed thereon relative to the pivot thereof that the weight of one chest tends to counter-balance the weight of the other, an ironing chest having an ironing face extending from one side and substantially the level of the horizontal axis of the laterally spaced roll, underneath the same and to a point adjacent the top side of the lower vertically spaced roll, an ironing chest having an ironing face engaging the top side of the lower vertically spaced roll, all of said ironing members being arranged to provide for continuous passage of work from the upper vertically spaced roll, around the laterally spaced roll, and to and around the lower vertically spaced roll, and a

- single supporting means for said last two ironing members including a supporting member pivotally mounted intermediate such ironing members with the ironing members so disposed relative to the pivot thereof that the weight of one chest tends to counter-balance the weight of the other, and means for moving said two supporting members simultaneously and in unison to bring the ironing members into ironing relation with the rolls. 5
5. In an ironing machine, a frame, a pair of substantially vertically spaced padded rolls rotatably mounted in said frame, a padded roll spaced laterally and substantially equi-distantly from both said vertically spaced rolls, said laterally spaced roll having a diameter greater than the space between said first named rolls, an ironing chest having an ironing face extending from the forward side and substantially the level of the horizontal axis of the upper vertically spaced roll, underneath the same and to a point adjacent the top forward side of the laterally spaced roll, ironing chest means having ironing faces engaging the major portion of the laterally spaced roll and extending over the top, around a portion of the rearward side and underneath the same to a point near the top rearward side of the lower vertical roll, ironing chest means having ironing faces engaging the major portion of the lower vertical roll and extending to the rear thereof, stripping and feeding means for stripping and feeding the work through the machine, feed means for feeding the work to the bite between the upper roll and the upper forward portion of the chest engaging the same, and delivery means for receiving the work from the rear portion of the lower ironing chest of the lower vertical roll. 10
6. In an ironing machine, the combination of two pressing elements, one of which is located below and to one side of the other, a lever pivotally supported intermediate the two elements, two pressing members adapted to coact with said elements, said members being carried by said lever, one on each side of said pivotal support and arranged so that one member moves upwardly into engagement with the upper element as the other member moves downwardly into engagement with the lower element, cam means contacting the lever for adjusting the position of the lever about its pivot, and the weight of the members being so arranged on the lever that one preponderates over the other in a direction to hold said lever in contact with the cam means. 15
7. In an ironing machine, a padded roll, a supporting member pivotally mounted for movement toward and from the periphery of the roll, an ironing chest yieldingly mounted upon said supporting member, coacting cam members one on the chest and the other on the supporting member for positioning the chest so that the curvature of its ironing surface is in matched nesting relation with that of the roll when the two are brought into engagement, one of said cam members being rigid with the supporting member and having an arcuate surface concentric with the pivot, and the other of said cam members being a block carried by the chest. 20
8. In an ironing machine, a padded roll, a supporting member pivotally mounted for movement toward and from the periphery of the roll, an ironing chest yieldingly mounted upon said supporting member, coacting cam members for positioning the chest with respect to the roll, one of said cam members being rigid with said supporting member and having an arcuate surface concentric with the pivot, the other of said cam members being a block adapted to coact with said arcuate surface, said block being rotatably mounted on an eccentric pin, and said pin being rotatably carried by said chest. 25
